UNITED STATES PATENT OFFICE.

CHARLES EARP FALCONBRIDGE AND JAMES WILLIAM LEWSLEY, OF NOTTINGHAM,
ENGLAND.

ELECTRICAL APPARATUS FOR CONTROLLING CURTAINS AND LIGHTS IN THEATERS.

1,322,774.

Specification of Letters Patent.

Patented Nov. 25, 1919.

Application filed June 2, 1919. Serial No. 301,321.

To all whom it may concern:

Be it known that we, CHARLES EARP FALCONBRIDGE and JAMES WILLIAM LEWSLEY, subjects of the King of Great Britain, residing at Nottingham, in England, have invented certain new and useful Improvements in Electrical Apparatus for Controlling Curtains and Lights in Theaters, of which the following is a specification.

This invention relates to improvements in electrical apparatus for controlling the curtains and lights in connection with the projecting screen or proscenium of a cinematograph or other theater and for like purposes, and its object is to provide means for effecting the beforementioned operations, which can be put into action, from any distant point, say for example from the operator's box or cabin, or from two or more distant points.

According to this invention the cords which operate the respective curtains are carried around a drum driven by an electro-motor, and the said cords are so disposed that the curtains are drawn open by rotating the drum in one direction, and closed by reversing the direction of rotation.

The electro-motor is controlled by three switches, that is, a starting switch with a no-volt release, an auxiliary switch in parallel with the starting switch, and a reversing switch. After starting, the auxiliary and reversing switches are automatically operated by means of mechanism actuated by tappets on the curtain cords, so as to stop the motor when the operation is completed, and at the same time reverse the armature connections ready for starting the motor again in the reverse direction.

Referring to the accompanying drawings—

Figure 1. is an elevation, and

Fig. 2. a plan of apparatus constructed and arranged according to our invention.

Like letters indicate like parts throughout the drawings.

The curtains (which are not shown) are arranged in the usual manner, and are drawn by means of two endless cords A and B, both of which are carried over a grooved drum C. This drum C is mounted on an axle C' carried by a standard D secured on a base plate E.

The drum C described is connected to and driven by means of an electro-motor F fixed

on the base plate E, through any suitable driving arrangement. As shown in the drawings, the driving connection consists of a grooved pulley G on the drum C, a grooved pulley F' on the shaft of the motor F, and a round driving belt H.

The motor is controlled by a starting switch with a no-volt release, an auxiliary switch which is in parallel with and short-circuits the starting switch, and a reversing switch in the armature circuit.

The starting switch can be placed at any distant point, while the auxiliary and reversing switches are for convenience placed near the motor driven drum C, and are moved over by tappets on the curtain cords acting on a longitudinal slide J.

This slide J works in guideways D' on the standard D previously described, and is provided at its ends with eyes J' through which the respective cords A and B are carried. The cords A and B are provided with clips K (only one of which is shown) which act as tappets and move the slide J in one direction near the completion of the curtain closing movement, and move it in the reverse direction near the completion of the curtain opening movement.

The auxiliary switch is carried in a casing L secured on the base plate E, and its operating lever M which is mounted on an axle N, is provided with a weight M' which moves over the vertical centers each movement. This lever M is disposed in the path of two tappets J' on the slide J, and when the latter is moved, the arm M is engaged by one of the said tappets J' and moved over the vertical center, when the weight M' comes into action and completes the movement.

The auxiliary switch comprises a wiper arm N' mounted on the same axle N as the operating lever M, and a fixed contact O over which the said arm N' moves.

The wiper arm N' only makes contact with the contact O and closes the switch when it is in its intermediate position, and on the completion of each movement of the lever M, which is effected by the action of the weight M', the wiper arm N' is moved clear of the contact O and opens the switch again.

In the same casing L as the supplementary switch described, is a reversing switch which is in series with both the starting and auxiliary switches, and the armature of the

motor F. This switch is of the usual construction, and comprises two contact arms P P' connected by an insulated connecting link P², and fixed contacts Q over which the arms P P' move. This switch is reversed each time the arm N' of the auxiliary switch is moved over as previously described, by means of tappets N³ on the arm N' engaging with a stud P⁴ on the connecting link P².

10 In parallel with the auxiliary switch described and in series with the motor F, is the starting switch R, which may be placed at any convenient distant position.

This switch may be an ordinary motor starting switch with a no-volt release, or as shown, it may be of the push-in type, which is held in the closed position by means of an electromagnet S in the circuit, against the action of a spring T, which latter opens the switch as soon as the current fails.

The electrical connections between the different parts of the apparatus are indicated by dotted lines in Fig. 1.

When the starting switch R is closed, the motor F is started by current supplied through this switch circuit and assuming that the curtains were closed they immediately commence to open. Near the completion of this opening movement, a clip K on one of the curtain cords engages with the eye J' and commences to move the main switch actuating slide J. The action of the latter first closes the auxiliary switch, which short-circuits the starting switch R, when the latter is released and automatically opens. The motor now continues to run with current supplied through the auxiliary switch, until the operating arm M on the latter reaches a certain point when the action of the weight M' on the latter carries the arm over to the other extreme position. This action opens the auxiliary switch again, stops the motor F, and at the same time moves over the arms P P' of the reversing switch, and reverses the armature circuit.

When the starting switch R is again closed, the same action takes place, but in this case the motor F runs in the reverse direction, the curtains are closed again, and near the completion of this movement, a clip K on the other cord moves the slide J in the reverse direction, the auxiliary and reversing switches are returned to their first position again, and the motor automatically stopped as before.

In order to control the lights, one of the curtain cords may be carried over and drive a pulley which is geared to preferably a light dimming rheostat and switch in series with the lights. This rheostat gradually cuts off the current as the curtains open, and performs the reverse operation when they are closed again. In the preferred arrangement

however the light dimming rheostat W is driven direct from the drum C by an independent belt V.

Apparatus such as described may be used for operating the curtains alone, or for operating one or more switches or other devices from a distance point, or be adapted to operate the curtains and two or more switches or devices simultaneously. It is also obvious that the control may be effected from one or more distant points, by providing starting switches disposed in parallel with each other and the auxiliary switch.

What we claim as our invention and desire to secure by Letters Patent is:—

1. In apparatus for controlling the curtains and lights in connection with a projecting screen or proscenium and for like purposes the combination of an electro-motor for operating the curtain, a starting switch with a no-volt release, an auxiliary switch which is moved over by the driven mechanism, and a reversing switch which is moved over by the auxiliary switch which latter is in parallel with and adapted to first close and short-circuit the starting switch and then open and stop the motor, substantially as described.

2. In apparatus for controlling the curtain and lights in connection with a projecting screen or proscenium and for like purposes, the combination of a cord drum for moving the curtain cords, an electro-motor for driving the drum, and three switches for controlling the motor, that is, a starting switch with a no-volt release, an auxiliary switch which is moved over by tappets on the curtain cords, and a reversing switch which is moved over by the auxiliary switch which latter is in parallel with and adapted to first close and short-circuit the starting switch and then open and stop the motor, substantially as described.

3. In apparatus for controlling the curtains and lights in connection with a projecting screen or proscenium and for like purposes, the combination of a cord drum for moving the curtain cords, an electro-motor for driving the drum, a starting switch with a no-volt release, an auxiliary switch which is moved over by tappets on the curtain cords, a reversing switch which is moved over by the auxiliary switch which latter is in parallel with and adapted to first close and short-circuit the starting switch and then open and stop the motor, a longitudinal slide provided with eyes through which the curtain cords are carried, tappets on the latter for engaging with and moving the slide, a weighted operating lever in connection with the auxiliary switch, and tappets on the slide to engage with and move the switch lever over the vertical center, substantially as described.

4. In apparatus for controlling the cur-

tain and lights in connection with a projecting screen or proscenium and for like purposes, the combination of a cord drum for moving the curtain cords, an electro-motor 5 for driving the drum, a starting switch with a no-volt release, an auxiliary switch which is moved over by tappets on the curtain cords, a reversing switch which is moved over by the auxiliary switch which latter is 10 in parallel with and adapted to first close and short circuit the starting switch and then open and stop the motor, and tappets on the arm of the auxiliary switch for moving over the reversing switch, substantially 15 as described.

5. In apparatus for controlling the curtain and lights in connection with a projecting screen or proscenium and for like purposes, the combination of a cord drum for

moving the curtain cords, an electro-motor 20 for driving the drum, a starting switch with a no-volt release, an auxiliary switch which is moved over by tappets on the curtain cords, a reversing switch which is moved over by the auxiliary switch which latter is 25 in parallel with and adapted to first close and short circuit the starting switch and then open and stop the motor, and a light dimmer connected to and controlled by the action of the curtain cord drum.

In testimony whereof we have signed our names to this specification in the presence of two subscribing witnesses.
